(57) **CLAIM**

The ornamental design for a pressure washer frame, as shown and described.

DESCRIPTION

FIG. 1 is a perspective view of a pressure washer frame showing my new design;

FIG. 2 is a right side view thereof;

FIG. 3 is a front view thereof;

FIG. 4 is left side view thereof;

FIG. 5 is back view thereof;

FIG. 6 is top view thereof; and,

FIG. 7 is a bottom view thereof.

The broken line showing of details in FIGS. 1-7 is included for the purpose of showing environmental portions of the pressure washer frame and forms no part of the claimed design.

The side bars on the frame are shown broken away to indicate that no specific length is claimed.
